UNITED STATES PATENT OFFICE.

BOULTBEE BROOKS, OF BIRMINGHAM, ENGLAND.

STICK SEAT.

Application filed September 27, 1927, Serial No. 222,268, and in Great Britain February 14, 1927.

This invention relates to stick-seats such as are used by sportsmen while shooting, or by persons attending race meetings or other outdoor functions; the said stick-seats being adapted, in the closed-up or collapsed condition, to be used as a walking-stick, but having a divided handle or upper portion arranged to fold outwards in opposite directions and assume a horizontal position in order to constitute a seat.

The principal object of the present invention is to provide for giving two different and alternative heights to the seat, thereby affording a comparatively high position as when only required to be used for a short time, and a lower and more comfortable position when the seat is required to be used for a longer period.

According to the invention, the usual looped handle is divided longitudinally and the two parts are arranged to fold outwards in opposite directions into horizontal positions to provide a seat, in the ordinary manner, but instead of the said handle parts being hinged directly to the main shank of the stick, as is usual, they are hinged respectively to the upper ends of another pair of outwardly-folding members (preferably in the form of plates or discs which may be padded or not) hinged at their lower ends to, and adapted to be supported in their horizontal position by, the stick shank, thus forming a lower seat, suitable fastening means being provided for holding the lower pair of folding members together in a vertical position when the upper handle members are turned down to form the higher seat and also when the said handle members are brought together for use as the handle of the stick.

Figure 1 of the accompanying drawings is a side elevation of a stick-seat according to the present invention, the same being shown in its extended position for use as a walking-stick.

Figure 2 is a vertical section on line 2—2, Figure 1, with the main stick in elevation.

Figure 3 is a section on line 3—3, Figure 1, taken through one of the catches for holding the lower seat members together.

Figure 4 represents a vertical section through the stick-seat with the upper seat members turned down to form a high-level seat.

Figure 5 is a plan.

Figure 6 is a vertical section through the

stick-seat with the low-level seat in position for use.

Referring to the above drawings, the stick-seat comprises the usual main metal shank or stick 1 at the summit of which a bracket or head 2 is provided for supporting the seat members. This bracket or head may consist of a casting or it may be in the form of a sheet-steel pressing suitably secured to the stick. The said bracket or lug is drilled with two laterally-separated horizontal bearing holes which receive pivot pins 3, 3, carried between ears 4, 4, at the lower or inner ends of two lower seat members 5, 5, consisting of substantially circular metal plates or discs adapted to come together in a vertical position. The seat members 5, 5, are adapted to be turned down in opposite directions into horizontal positions, in alignment with one another, as shown in Figure 6, in order to constitute a low-level seat, and for this purpose they are provided near their inner ends with flanges 6, 6, which, in the horizontal position of the seat members, engage the outer faces of the bracket or head 2, and act as stops. When the seat members or plates 5, 5, are turned into a vertical position, they are adapted to be held together by catches or fastening devices conveniently consisting of two transversely-disposed blade springs 7, 7, fixed by a screw or rivet 8, 8, to the upper part of one of the seat members and arranged to overlap the adjacent seat member, the said catches each being provided with a hole adapted to snap into engagement with a stud 9, 9, on the said adjacent seat member. The said seat plates 5, 5, may be suitably padded upon their upper or inner faces to provide a comfortable seat; and at their upper or outer ends looped or stirrup-shaped handle members 10, 10, are hingedly connected at 11, 11. These handle members are adapted to be brought together in a vertical position, as in Figures 1 to 3, to constitute a handle to the stick, but are also adapted to be turned outwards in opposite directions into horizontal positions (the seat plates being maintained in their fastened-together vertical position) and to be supported in these positions by suitable stops, in order to form a high-level seat, as shown in Figure 4. These stops may be constituted by the outer faces of the hinge knuckles or lugs 12 at the outer ends of the seat members 5, 5, the said outer faces of these knuckles or lugs being engaged by the inner end parts 13 of

the handle members 10 when the latter are turned down with the horizontal position shown in Figure 4. In use, when the device is to be employed as a walking stick, the 5 low-level seat plates 5, 5, are fastened together in their vertical positions and the handle members 10, 10, also brought together in a vertical plane, as in Figures 1 to 3, when the said members 10, 10, may be used as the handle 10 to the stick. If a seat is temporarily required, the handle members 10, 10, are turned down into a horizontal position, as in Figures 4 and 5, the low-level seat-plates 5, 5, still being fastened together in a vertical position. 15 when the said handle members 10, 10, being in alignment, form a high-level seat. If, however, a seat is required for any considerable length of time, and greater comfort desired, the low-level seat-plates 5, 5, are 20 unfastened and opened out into their horizontal positions to form a seat, as in Figure 6, the handle members 10, 10, depending from their outer ends.

Having fully described my invention, what 25 I desire to claim and secure by Letters Patent is:—

1. A stick-seat comprising a main support, folding seat members hinged to said main support, means for supporting said seat members in a horizontal position for use as a low-level seat, means for holding together said seat members in a vertical position, folding handle members hinged to said seat members, and means for supporting said handle members in a horizontal position for use as a high-level seat. 30

2. A stick-seat comprising a main stick,

seat members hinged to the upper end of said stick and adapted to fold outwardly, means for supporting said seat members in a horizontal position for use as a low-level seat, means for holding together said seat members in a vertical position, handle members hinged to the outer ends of said seat members and adapted to fold outwards, and means for supporting said handle members in a horizontal position for use as a high-level seat. 40 45

3. A stick-seat comprising a main stick, a head at the summit of the stick, seat members hinged to the said head and adapted to fold outwards, stops on the seat members co-operating with the head to support the seat members in a horizontal position for use as a low-level seat, fastening means for temporarily holding together said seat members in a vertical position, handle members hinged to the outer ends of said seat members and adapted to fold outwards, and stops for supporting said handle members in a horizontal position for use as a high-level seat. 50 55 60

4. A stick-seat comprising a main support, folding seat members hinged to said main support, means for supporting said seat members in a horizontal position for use as a low-level seat, a spring catch on one seat member adapted to hold together the seat members in a vertical position, folding handle members hinged to said seat members, and means for supporting said handle members in a horizontal position for use as a high-level seat. 65 70

In testimony whereof I have hereunto set my hand.

BOULTBEE BROOKS.
